CLAIM

The ornamental design for footwear, as shown and described.

DESCRIPTION

FIG. 1 is a front perspective view of an embodiment of footwear.

FIG. 2 is a front view of the embodiment of FIG. 1.

FIG. 3 is a back view of the embodiment of FIG. 1.

FIG. 4 is an inner side view of the embodiment of FIG. 1.

FIG. 5 is an outer side view of the embodiment of FIG. 1.

FIG. 6 is a top view of the embodiment of FIG. 1.

FIG. 7 is a bottom view of the embodiment of FIG. 1.

FIG. 8 is a front perspective view of another embodiment of footwear.

FIG. 9 is a front view of the embodiment of FIG. 8.

FIG. 10 is a back view of the embodiment of FIG. 8.

FIG. 11 is an inner side view of the embodiment of FIG. 8.

FIG. 12 is an outer side view of the embodiment of FIG. 8.

FIG. 13 is a top view of the embodiment of FIG. 8; and,

FIG. 14 is a bottom view of the embodiment of FIG. 8.

The broken line showing of the strap, the interior, and the tread is for illustrative purpose only and forms no part of the claimed design.
